7 Claims. (Cl. 33—75)

1

This invention relates to clinographs of the type intended for use against a straight edge and having two relatively movable parts, namely a part (herein referred to as the segment) in the form of a segment of a circle, and a generally triangular part (herein referred to as the bearing plate) having two straight sides at right angles to one another and a third concave side shaped to receive the circumferential edge of the segment so that the latter can slide along it, markings or scales being provided on the parts to indicate their relative angular position.

According to the present invention the chord of the segment subtends an angle of less than 60° at the centre of the arc. Thus, for the same size of instrument, the radius of the circle from which the segment is taken is increased in comparison with known arrangements where the segment subtends an angle greater than 90° , and is always greater than the length of the chord. Hence it is possible to obtain a greater degree of accuracy and to provide scales from which to read off directly angles to within fractions of degrees and their trigonometrical functions. In order to obtain results of the same order of accuracy with an instrument having a segment subtending more than 90° as previously proposed, it would be necessary to employ a substantially larger instrument.

The invention may be carried into practice in various ways, but will be further described, together with two specific embodiments given by way of example, with reference to the accompanying drawings in which:

Figures 1 to 5 are diagrams indicating how the size of an instrument of given accuracy can be progressively reduced in accordance with the invention,

Figures 6 and 7 are views respectively of opposite sides of an instrument corresponding to the diagram of Figure 4, and,

Figures 8 and 9 are views respectively of opposite sides of an instrument corresponding to the diagram of Figure 5.

Each embodiment comprises a clinograph or adjustable set-square of suitable sheet material including a bearing plate A in the shape of a cut away right-angled triangle. From this triangle is cut away a segment of a circle whose chord comprises the greater part of the hypotenuse. A separate segment B of the same size and of similar sheet material is let into the bearing plate so that its chord can lie along the hypotenuse in one position, and the segment and bearing plate are adapted to slide in relation to

2

each other along the perimeter of the former, by a tongue-and-groove joint, similar to but deeper than that which is employed in a slide-rule, the tongue being carried by the bearing plate and the groove being cut in the segment.

The object of the present invention is to provide a clinograph which will enable the chord of the segment to be set at any required angle, with the greatest accuracy possible for an instrument of given size. The accuracy of such an instrument is directly proportional to the radius of the circle, since, for a given error in adjusting the scale setting, the error in the inclination of the chord is inversely proportional to the radius, and similarly an increase of the radius enables each degree of arc to be subdivided into a greater number of parts.

Accordingly the present invention aims at employing the maximum radius with an instrument of a given size, or conversely reducing to a minimum the size of an instrument employing a given radius.

To enable the instrument to be set to angles down to 0° while the one side is placed against a straight edge it is essential that that side produced should not intersect the circle of which the segment forms a part. Thus as indicated diagrammatically in Figure 1, if a segment of a circle C is employed the tangent D represents the limiting position of this side towards the centre of the circle. On the other hand, if this side is far beyond the tangent the size of the triangle is increased with no corresponding advantage. These considerations determine the distance of the one side from the centre of the circle within fairly close limits.

In a prior construction the other side has also been made to lie along or outside the tangent as indicated at E, the angle subtended by the chord being approximately 90° as indicated at F. With such a construction it will be appreciated that the range of movement of the segment is unnecessarily great since it can engage the bearing plate with reasonable accuracy in any position from about that shown at F¹ to about that shown at F², so that by using both the edges D and E against the straight edge and also inverting the instrument it is possible to cover the complete range of possible inclinations several times over.

By restricting the range of movement in accordance with the invention so as to cover merely what is needed the size of the instrument for a given accuracy can be considerably reduced.

In the first place it would be possible merely to reduce the angle subtended by the chord to

an angle less than 90° , for example to 60° , whilst still retaining a 45° instrument. Figure 1 indicates this at G and the consequent reduction in size of the instrument is indicated by the hatched area G^1 .

By adopting a 30° instrument instead of a 45° instrument a similar reduction of size is effected as indicated by the hatched area H^1 in Figure 2, which still shows an arrangement in which neither side of the instrument when produced would intersect the circle.

With the arrangement shown in Figure 2 the chord H subtends an angle of 60° at the centre and can be moved from a position H^2 at an angle of 0° to the longer side D. It could also be moved to a position H^3 at an angle of 0° to the shorter side E without fouling a straight edge against which that side was placed, but in the first place there would then be no overlap to support the segment and secondly the range of movement so provided would still be unnecessarily great, bearing in mind the possibility of putting either edge against the straight edge and inverting the instrument.

The former difficulty can be overcome and a further reduction of size rendered possible by restricting the extent to which movement of the segment in one direction is relied on with the short side against a straight edge. Thus in the arrangement shown in Figure 3, of the range of angles from 0° to 90° , a range from 0° to 60° can be covered with the longer side D against the straight edge, by moving the chord H 30° in either direction from the position H in line with the hypotenuse to the positions H^3 and H^4 . The remaining 30° can be covered with the shorter side against the straight edge by moving the chord 30° in one direction only, namely away from the straight edge to the position H^3 . This enables the short side to be brought into the position J and gives a further reduction in size for a given radius as indicated by the hatched area J^1 in Figure 3.

It will be noted that in Figure 3 the inclination of the hypotenuse to the longer side is half the range of movement of the chord, thus ensuring that the overhang, and hence the remaining overlap, will be the same when the segment is in each of its extreme positions.

It still remains to settle the angle subtended by the segment at the centre of the circle, which, for a given angular range, determines how much overlap remains when the segment is in its extreme positions, and further materially affects the size of the instrument for a given radius.

It can be shown trigonometrically that for a 30° instrument the length a of the longer side D of the instrument shown in Figure 4 is given by the equation:

$$a = \sqrt{3}r[1 - \cos(30^\circ + \theta)]$$

where r is the radius of the arc, and 2θ is the angle subtended by the arc at the centre.

In the arrangement of Figure 3 the arc subtends an angle of 60° and with this angle the overlap in the extreme positions is 50% of the arc as shown in Figure 3. It is, however, found that this is unnecessarily great and an overlap of about 25% is in general sufficient, making the angle subtended by the segment very slightly over 40° as indicated in Figure 4. Thus in the preferred embodiment of the invention the length of the longer side is given by the equation set out in which 2θ has a value of approximately 40° .

This enables a further reduction of size to be achieved as indicated in Figure 4, in which the hypotenuse is brought down to the position K whilst the short side is further brought in to the position L, representing a total reduction of size indicated by the hatched area L^1 . Figure 4 represents the preferred embodiment of the invention which is described in greater detail below with reference to Figures 6 and 7.

For the sake of greater convenience, at the sacrifice of a certain amount of accuracy for a given size, the arrangement of Figure 4 may in certain cases be replaced by the modification shown in Figure 5 in which the movement of the segment with the longer side in contact with the straight edge is only relied upon to cover the range from 0° to 45° , by movement of the chord from a position K^1 to a position K^3 . Accordingly the range from 45° to 90° must be covered with the shorter side in contact with the straight edge and the shorter side must be brought out to a position M in which it can be placed against the straight edge with the segment in the position K^3 , namely at an angle of 45° .

In this case to ensure that the inclination of the hypotenuse to the longer side would be half the range of movement of the chord, and hence that the overlap would be the same when the segment is in each of its extreme positions, this inclination would be $22\frac{1}{2}^\circ$, but the proportions would then be bad and the convenience of a 30° set-square is such that it is preferred to employ an angle of 30° in this case also.

In the arrangement shown in Figure 5 the amount of overlap, and the size of the instrument for a given radius, again depends on the angle subtended by the arc at the centre. The length b of the longer side D of the instrument is in this case given by the formula:

$$b = \sqrt{3}r[1 - \cos(30^\circ + \theta)] + r \sin(45^\circ + \theta) - r \sin(30^\circ + \theta)$$

where r and θ have the meanings already referred to.

In order to accommodate a single scale reading from 0 to 45° the arc cannot subtend an angle than 45° and a small margin is desirable. Accordingly in a modified form of the invention the length of the instrument is given by the above formula in which the value of 2θ lies between 45° and 46° .

Figures 1 to 5 indicate in each case the theoretical minimum size of the instrument and in practice a small amount would in each case have to be added to provide necessary margins. In the constructions described these margins are reduced firstly by the fact that of the tongue-and-groove connection between the segment and the bearing plate the tongue is formed on the bearing plate and the groove on the segment, and secondly by the fact that the corners do not extend to the points at which the longer and shorter sides would touch the circle, so that long thin points on the bearing plate tend in any case to be avoided.

The sharp tips of the segment are cut off to prevent accidental damage, enough being retained to allow the chord to mate with the end of the tongue of the joint carried by the bearing plate so that the hypotenuse can be formed by a continuous edge. In the construction indicated in Figure 4 and described in more detail below with reference to Figures 6 and 7, sufficient may be cut off, at 60° to the chord, to allow an angle

5

of 59° to be read when the short side is in contact with the straight edge.

In the construction of which opposite sides are shown in Figures 6 and 7 (and which corresponds to the diagram of Figure 4), an angular scale N of 30° extent is marked symmetrically on one side of the segment (shown in Figure 6) along its perimeter and is subdivided down to units of 10 or even 5 minutes. When in the zero position, the zero end of this scale coincides with an index mark P^1 on the bearing plate; and when inclined at 30° , at which position the chord coincides with the hypotenuse, this end will coincide with a second index mark P^2 on the plate. Angles from 30° to 60° are read against this second index mark, the longer side D of the bearing plate being in contact with the straight edge in both cases. When the shorter side L of the bearing plate is in contact with the straight edge, angles from 60° to 90° are read in the opposite direction on the same scale against the first index mark P^1 on the bearing plate. The scale is numbered so that it can be read in both directions without confusion. Vernier scales are placed adjacent to each index mark, and a short extension of the scale of about one degree enables these to be used at the extreme limiting readings.

The arc of the bearing plate is provided with a scale P of sines of angles between 0° and 30° extending between the two index marks. Thus the sines of angles between 0° and 30° can be read directly off this scale against the zero end of the segment scale, the sine corresponding in each case to the angle read on the segment.

The sines of angles from 30° to 60° are read on a second scale Q , placed on the reverse side of the bearing plate as shown in Figure 7, against an index mark R^1 on the segment. Sines of angles from 60° to 90° are graduated at R on the segment and read against the upper end Q^1 of the scale Q on the bearing plate when the shorter side L of the latter is placed against the straight edge.

For general use in a drawing office it may be of advantage to have a simple scale reading from 0° to 45° which is sufficient to allow lines to be drawn in any direction, those inclined from 45° to 90° being drawn with the shorter side in contact with the straight edge. For this purpose in the embodiment of which opposite sides are shown in Figures 8 and 9 respectively (and which corresponds to the diagram of Figure 5) the bearing plate is extended to enable the segment to clear the shorter side produced when the chord is at 45° , so that either side can be placed against the straight edge for all working positions of the segment. A shoulder S^1 is placed on the tongue S carried by the bearing plate to engage with a corresponding step in the recess on the segment when the chord K of the latter is inclined at 45° . This allows the chord to be set at 45° without reference to the scale, enabling the instrument to serve as a 30° or 45° set-square. As shown in Figure 8 the scale T from 0° to 45° is placed on the bearing plate, thus enabling the arc of the bearing plate to be made 45° plus a small allowance necessary to allow the ends of the scale to stand clear of the hypotenuse. An index mark U^1 , preferably combined with a vernier, is provided on the segment.

On the opposite face of the instrument seen in Figure 9 a scale of sines is provided, the sines of angles from 0° to 45° being in a scale V on the bearing plate and those above 45° in a scale W

6

on the segment. It is not possible to extend a scale to the pointed ends of the segment, which are cut off, but since the sines of angles above 82° differ from unity by less than one per cent and are seldom required, the scale can be shortened sufficiently to enable it to be placed on the segment.

The following preferred arrangement satisfies the above requirement and provides a clear scale.

10 The scale V of sines of angles from 0° to 45° is placed on the bearing plate, and divided at intervals of $.01$ by short lines extending from the arcuate edge to a continuous line at the back, thus forming a series of cells which are grouped 15 in the normal manner by extending the line at every fifth and tenth division. Within each cell divisions of $.002$ or $.001$ are placed (but for clarity are omitted from the drawing). All the values are read against an index mark W^1 on the segment which corresponds with the zero end of the scale V when the chord K is parallel to the longer side D of the bearing plate.

A similar scale W of sines of angles above 45° is placed on the segment, and read against 25 an index mark V^1 on the bearing plate, the shorter side M of the latter being in contact with the straight edge.

If the scale W extended from end to end of the segment, with a segment subtending 45° , the 30 index V^1 on the bearing plate would have to be 15° from the end of the scale W nearer the longer side D so as to register with the end of the scale W on the segment when the latter had been shifted through 30° from a position (K in Figure 5) with the chord along to the hypotenuse to a position (K^1 in Figure 5) with the chord parallel to the longer side D . Similarly the index W^1 would be 15° from the end of the scale W nearer to the short side M .

40 Since the scale cannot extend to both ends of the segment, the scale W is shifted through $1^\circ 15.6'$ and the index line V^1 on the bearing plate is moved by the same amount; so that it will be at a point $16^\circ 15.6'$ from the zero of the scale V 45 on the latter. This angle is $\sin^{-1}.25$, so that the mark V^1 will cross the bearing plate scale V between two cells. Moreover in the zero or 90° position it will lie beyond the end of the segment (although it would correspond to the end of the scale W on the latter if it could be carried so far). Sines of angles very near 90° cannot therefore be read but as these differ from unity by not more than about $\frac{1}{4}\%$ this is immaterial. The index mark W^1 on the segment similarly corresponds to 50 an angle on the scale W of 90° minus $16^\circ 15.6'$ or $73^\circ 44.4'$ of which the sine is $.96$. Therefore this mark also crosses the scale W on the segment between two cells and does not interfere with the scale. The end X of the segment nearer the 55 short side D is preferably cut off at an angle of 45° with the chord, so that it lies parallel to the short side when in the extreme 45° position. Since the tongue S of the joint between the parts is broad at this end, it is possible to remove a considerable amount from the segment while allowing the tongue to continue the line of the hypotenuse when the chord is inclined at 30° . The angular scales in both these embodiments are divided in a similar manner to the sines, each cell containing one degree while the smaller divisions of 10 or 5 minutes are grouped inside the cells.

60 It will be clear that if required, additional or alternative scales could be marked on the instrument, such as tangent scales, or a plain scale of degrees alone may be provided.

What I claim as my invention and desire to secure by Letters Patent is:

1. A clinograph comprising a bearing plate and a segment together forming a complete thirty degree right angle triangle, the bearing plate having two straight sides at right angles to one another and a concave arcuate side, and the segment having a straight chord and a convex arc fitting the concave arc of the bearing plate and adapted to slide along it, angular scales being provided to indicate the inclination of the chord to the straight sides of the bearing plate, wherein the arc of the segment subtends an angle not greater than 60° at the centre, and the longer side of the bearing plate, when produced, lies just outside the circle of which the segment forms a part, whilst the shorter side, when produced, intersects that circle.

2. A clinograph as claimed in claim 1, the bearing plate having two straight sides at right angles to one another and a tongued concave arcuate side, and the segment having a straight chord and a convex grooved arc, whereof the groove fits the tongue of the concave side of the bearing plate to permit relative sliding.

3. A clinograph comprising a bearing plate and a segment together forming a complete thirty degree, right angled triangle, the bearing plate having two straight sides at right angles to one another and a concave arcuate side, and a segment having a straight chord and a convex arc fitting the concave arc of the bearing plate and adapted to slide along it, angular scales being provided to indicate the inclination of the chord to the straight sides of the bearing plate wherein the arc of the segment subtends an angle of not more than 60° at the center, the chord being movable from an inclination of zero to an inclination of 60° to the longer side without the segment intersecting the longer side when produced, and wherein the shorter side terminates close to the end of the arc of the bearing plate so that the chord constitutes substantially the whole of the hypotenuse.

4. A clinograph as claimed in claim 3 in which the distance of the hypotenuse of the triangle from the centre of the circle is such that the segment arc subtends an angle of approximately 40° at the centre.

5. A clinograph as claimed in claim 3 in which the dimensions are such that the overlap between the segment and the bearing plate when the former is in either of its extreme positions

is approximately a quarter of the total arc of contact between them.

6. A clinograph comprising a bearing plate and a segment together form a complete thirty degree, right-angled triangle, the bearing plate having two straight sides at right angles to one another and a concave arcuate side, and a segment having a straight chord and a convex arc fitting the concave arc of the bearing plate and adapted to slide along it, at least one angular scale being provided to indicate the inclination of the chord to the straight sides of the bearing plate, in which the length a of the longer side of the bearing plate is given by the formula:

$$a = \sqrt{3r[1 - \cos(30^\circ + \theta)]}$$

where r is the radius of the arc, and 2θ is the angle subtended by the arc at the centre and has a value of approximately 40° .

7. A clinograph comprising a bearing plate having two straight sides at right angles to one another and a concave arcuate side, and a segment having a straight chord and a convex arc fitting the concave arc of the bearing plate and adapted to slide along it, angular scales being provided to indicate the inclination of the chord to the straight sides of the bearing plate, wherein the arc of the segment subtends an angle not greater than 60° at the center, and wherein the arcs of the segment and bearing plate are of approximately the same length and, when the segment is set to a position in which its chord is at 30° with one of the straight sides of the bearing plate, each end of the segment arc approximately coincides with the corresponding end of the bearing plate arc, and wherein one of the straight sides of the bearing plate when produced lies close to but just outside the circle of which the segment forms a part whilst the other straight side of the bearing plate when produced intersects the circle of which the bearing plate forms a part.
